ROLAND G. MARX, OF PALO ALTO, AND LEONARD F. FULLER, OF SAN FRANCISCO, CALIFORNIA, ASSIGNEES TO FEDERAL TELEGRAPH COMPANY, OF SAN FRANCISCO, CALIFORNIA, A CORPORATION OF CALIFORNIA.

RADIOTELEGRAPHY.

1,316,172.

Specification of Letters Patent. Patented Sept. 16, 1919.

Application filed August 13, 1917. Serial No. 185,908.

To all whom it may concern:

Be it known that we, ROLAND G. MARX and LEONARD F. FULLER, citizens of the United States, and residents, respectively, 5 of Palo Alto, Santa Clara county, and the city and county of San Francisco, both in the State of California, have invented certain new and useful Improvements in Radio-telegraphy, of which the following is a 10 specification.

The invention relates to a means of signaling and particularly to means of signaling with arc radio transmitters.

An object of the invention is to provide 15 means for signaling which requires the handling of only relatively small currents.

Another object of the invention is to provide means for signaling involving extinguishing and re-igniting the arc.

20 The invention possesses other advantageous features, some of which, with the foregoing, will be set forth at length in the following description, where we shall outline in full that form of the invention which we 25 have selected for illustration in the drawings accompanying and forming part of the present specification. It is to be understood, however, that the invention as expressed in the claims is not limited to the specific embodiment shown in the drawings.

Referring to said drawings:

Figure 1 is a diagrammatic representation of one form of the system of our invention.

Fig. 2 is a diagrammatic representation of 35 a modified form.

Fig. 3 is a diagrammatic representation of the potential curve across the arc.

The potential curve 2 taken across the arc 40 is a very irregular curve having sharp peaks 3 without which the arc cannot oscillate and we provide means for robbing the potential curve of its peaks. When the curve is so 45 robbed of its peaks, the arc is extinguished and radiant energy is not emitted from the antenna circuit. Signaling is accomplished by alternately extinguishing and reigniting the arc at telegraphic speed.

The transmission system comprises an arc 50 oscillation generator 4, which is grounded on one side, preferably the negative, and connected on the other side to the antenna 5 through the variable inductance or loading

coil 6. Direct current is supplied to the arc oscillation generator by the generator 7 and a choke coil 8 is arranged in the lead 9 connected to the antenna side of the arc. The arc is subjected to a strong transverse magnetic field produced by the magnet coil 12, which may be separately excited by the generator 13.

The potential wave produced by the arc has a very jagged form, developing sharp peaks, and the wave may be robbed of these peaks at the arc or in the loading coil. This jagged wave form is impressed upon the first 60 few turns of the antenna loading coil 6. In Fig. 1 we have shown the means for robbing the wave form of its peaks connected across the lower turns of the loading coil and in Fig. 2 we have shown this means connected 70 across the arc.

Connected across the lower turns of the loading coil (Fig. 1) is a circuit containing an electrolytic lightning arrester 14 which acts as a potential valve and a signaling key 75 15. The lightning arrester is made up of two or more aluminum cells, connected in series, each cell consisting of two aluminum plates on which has been formed by chemical or electro-chemical processes, a film 80 of hydroxid of aluminum, the plates being immersed in a suitable electrolyte. When the jagged wave form is impressed on the arrester, the film opens, as it were, and a current limited only by the internal resistance of the cells, which is low, flows through 85 the arrester. The part of the potential curve eliminated by the cells is indicated by the shaded portions 16 of the potential curve. When the signaling key 15 is closed, 90 the wave form is robbed of its potential peaks which discharge through the aluminum lightning arrester and the arc is extinguished. In Fig. 2, the circuit containing the lightning arrester 14 and the signaling 95 key 15 is connected across the arc and when the key is closed the arc is likewise extinguished.

Ordinarily, when the key circuit is again opened, the arc will not reignite and means 100 should be provided for reigniting the arc immediately, so that the key may be operated at telegraphic speed. One form of means which may be employed for reigniting the

arc is shown herein, this means being so arranged that the arc is ignited as the lightning arrester circuit is opened. Connected across the arc is a spark circuit containing the 5 spark gap 17, the secondary of the transformer 18 and the capacity 19 shunting the secondary. A stopping resistance 21 is arranged between the spark gap and the antenna side of the arc to prevent direct current sufficient to maintain an arc across the 10 spark gap from following the radio frequency current across the spark gap and passing through the secondary. The primary of the transformer is in series with an 15 alternating current generator 22 and a switch 23 in the primary circuit is attached to the key 15 by an insulating rod 24. When the lightning arrester circuit is opened, the circuit through the primary is closed, producing 20 a high potential in the spark circuit and producing a spark across the spark gap which sets up radio frequency surges which ignite the arc.

We claim:

- 25 1. An arc system for radio signaling comprising an arc, a current supply and an antenna circuit connected to the arc, and a circuit containing an aluminum lightning arrester arranged to shunt a portion of the oscillations produced by said arc.
2. An arc system for radio signaling, comprising a current supply and an oscillation circuit connected to an arc and a circuit containing a potential valve arranged to shunt 35 a portion of the oscillation circuit.
3. An arc system for radio signaling comprising a current supply and an oscillation circuit connected to an arc and a circuit containing a potential valve and a signaling key 40 arranged in shunt on a portion of the oscillation circuit.
4. An arc system for radio signaling comprising a current supply and an oscillation circuit connected to an arc and a circuit 45 containing an aluminum lightning arrester and a signaling key arranged in shunt on a portion of the oscillation circuit.
5. An arc system for radio signaling comprising an arc which produces an oscillating

current having a peaked potential wave 50 form, means for robbing the wave of its peaks whereby the arc is extinguished and means for reigniting the arc.

6. An arc system for radio signaling comprising a current supply and an oscillation 55 circuit connected to an arc, a circuit containing a potential valve adapted to be shunted across a portion of the oscillation circuit, whereby the arc is extinguished, and means for reigniting the arc. 60

7. An arc system for radio signaling comprising a current supply and an oscillation circuit connected to an arc, a circuit containing a potential valve and a signaling key shunting a portion of the oscillation circuit, the closing of said key serving to extinguish the arc, and means operative in time with the opening of said key for reigniting the arc. 65

8. An arc system for radio signaling comprising a current supply and an oscillation circuit connected to an arc, a circuit containing an aluminum lightning arrester, and a signaling key shunting a portion of the oscillation circuit, the closing of said key serving to extinguish the arc, and means operative in time with the opening of said key for reigniting the arc. 70

9. The method of producing radio signals with an arc which produces an oscillatory 75 current having a peaked potential wave form, which consists in robbing the wave of its peaks.

10. The method of producing radio signals which consists in producing an oscillatory current having a peaked potential wave form in an oscillating circuit and intermittently removing the peaks by shunting the circuit. 85

In testimony whereof, I have hereunto set 90 my hand at Honolulu, Territory of Hawaii, this 19th day of July, 1917.

ROLAND G. MARX.

In testimony whereof, I have hereunto set 95 my hand at the city and county of San Francisco, State of California, this 31st day of July, 1917.

LEONARD F. FULLER.
